UNITED STATES PATENT OFFICE.

HENRY B. KEIPER, OF LANCASTER, PENNSYLVANIA.

DESIGN FOR A GEAR-TRAIN CASING FOR ROTARY BLOWERS.

SPECIFICATION forming part of Design No. 34,884, dated July 30, 1901.

Application filed June 10, 1901. Serial No. 64,049. Term of patent 14 years.

To all whom it may concern:

Be it known that I, HENRY B. KEIPER, a citizen of the United States, residing at Lancaster, in the county of Lancaster and State of Pennsylvania, have invented and produced a certain new, useful, and original Design for Gear-Train Casings for Rotary Blowers; and I do hereby declare the following to be a full, clear, and exact description of the invention, so such as will enable others skilled in the art to which it appertains to make and use the same.

In the accompanying drawing, which forms a part of this specification, I have illustrated a perspective view of a gear-train casing for rotary blowers embodying my new design.

As shown in said drawing, the said casing consists of two sections or side portions (denoted by the letters A A') having the appearance of being divided upon a line cutting the inturned marginal portions or flanges a a' of said sections, so as to separate the interior side walls thereof sufficiently to receive and inclose between them a train of gearing, and a base portion B, which is of tubular form to receive the shaft of a rotary blower, said tubular portion having a rib or projection b' for engagement with or between suitable clamping devices by which the said casing may be mounted upon and secured to a stand or support therefor and having at its forward

end a terminal flange or attaching-plate B', suitably apertured to receive bolts for attachment to the casing of a rotary blower, and said sections of the casing having a plurality of external tubular bosses or projections A² 35 A² to receive the boxes or bearings for the shafts or spindles of a train of gearing housed within the casing and also having coincidentally-apertured protuberances or ears a² a³ to receive fastening-bolts, as shown. 40

As will be seen, the leading or material features of my design reside in a gear-train casing having the appearance of being formed in longitudinally - separable sections provided with lateral tubular bosses or projections and 45 a tubular base portion having a perforated attaching-plate at the front end of the casing.

Having thus described my invention, what I claim as new, and desire to secure by Letters Patent of the United States, is— 50

The design for a gear-train casing for rotary blowers, substantially as shown and described.

In testimony whereof I affix my signature in presence of two witnesses.

HENRY B. KEIPER.
